DESIGN FOR A SEWING MACHINE HOUSING

Norman V. Christensen and Ned Leo Wallenberg,
Chicago, Ill., assignors to Union Special Ma-
chine Company, Chicago, Ill., a corporation of
Illinois

Application October 16, 1945, Serial No. 122,866

Term of patent 14 years

(Cl. D70—1)

To all whom it may concern:

Be it known that we, Norman V. Christensen and Ned L. Wallenberg, citizens of the United States and residents of Chicago, county of Cook, and State of Illinois, have invented a new, original, and ornamental Design for Sewing Machine Housings, of which the following is a specification, reference being had to the accompanying drawings, forming a part thereof, in which:

Fig. 1 is a front elevational view of a sewing machine housing showing our new design,

Fig. 2 is an end elevational view of the hous-
ing taken from the righthand end of Fig. 1,

Fig. 3 is a top plan view of the housing, and

Fig. 4 is an end elevational view of the hous-
ing taken from the lefthand end of Fig. 1.

We claim:

The ornamental design for a sewing machine
housing, as shown.

NORMAN V. CHRISTENSEN.
NED LEO WALLENBERG.
